UNITED STATES PATENT OFFICE

ROBERT WERSCHKY, OF DENVER, COLORADO
PROCESS FOR FINISHING SHOES

Application filed August 13, 1928. Serial No. 299,459.

No Drawing.

This invention relates to improvements in processes for finishing leather and has reference more particularly to a process for coloring shoes.

5 It is becoming very popular for women and girls to wear shoes that are colored to harmonize with their dresses and this makes it necessary to carry a large number of colors as well as the different sizes and this increases unreasonably the amount of stock 10 to be carried by a dealer. It is evident that if a dealer is in position to color any shoe as desired, he will be in position to match the color of any dress without making it necessary to carry a big supply of shoes of different colors.

It is the object of this invention to produce a method of coloring shoes that can readily be practiced by any shoe dealer and 20 to produce the materials for carrying out the method so that the dealer or any one else may quickly color a pair of shoes to the desired color.

It is evident that it is often desirable to 25 alter the color of shoes to harmonize with other and different colored dresses and by means of the process and materials herein described, this can readily be done.

As nearly all new shoes and all old shoes 30 have a finished surface, it is first of all necessary to remove this finish and this is effected by applying to the shoes a varnish remover of the type herein described, by means of 0 or 00 steel wool; this loosens the finish and 35 opens the pores of the leather. The shoe is then carefully wiped by a piece of cloth and left to dry for about fifteen minutes. The next step is to apply the coloring which 40 comprises a fluid varnish remover in which is dissolved or suspended a suitable dye or pigment. The varnish remover penetrates the leather and the pigment or dye becomes evenly distributed over the surface and in the 45 pores and does not form a layer that will break and peel, but acts rather as a penetrating dye that gives the desired color and leaves the surface of the leather in its natural shape. If the desired appearance is not 50 attained by means of a single application of

the coloring material, another coat may be applied as soon as the first coat has dried.

After the color has been applied, the shoe is left to dry for two to four hours, or as long as necessary. If the shoe is placed in a 55 fan, it will dry much faster than otherwise.

After the color coat has dried, a finishing coat is then applied. The finishing coat is formed by a mixture of lacquer, castor oil 60 and linseed oil in the proportion of three parts of lacquer to one part each of the castor and linseed oil. This finishing coat gives the surface the necessary luster and provides a protective film over the colored surface. 65

The lacquer protects the surface of the leather from the effect of moisture and makes it possible to clean the shoes by means of a dry or a moist rag, thus making it possible to retain the finished appearance for a long time. 70 If the color is to be altered, this can be readily done by first removing the finish by means of a varnish remover and then applying the new color as above described. The varnish

remover employed is of the usual type, sometimes called "paint remover" and contains solvents on the order of benzol, other solvents on the order of alcohol and in addition cyclic CH_2 hydrocarbons, as hexahydrobenzol or derivatives of cyclic hydrocarbons 80 as adipin ketone. Instead of the cyclic CH_2 hydrocarbons mentioned any of their equivalents, such as the cyclic paraffins, including cyclohepatane or pentamethylene, vinyl trimethylene, etc., may be used. It is also possible to employ such intermediate derivatives 85 of these cyclic paraffins or cyclic hydrocarbons as acetyltrimethylene, deteramethylene ketone adipin, ketone, etc.

For the purpose of this invention twenty 90 per cent of castor oil and twenty per cent of linseed oil are mixed with sixty per cent of the exudations of the *Rhus vernicifera*.

The pigment or color may be any standard dye which is mixed with the varnish remover in the proper proportions. 95

From the above it will be apparent that I have produced a simple and effective method for applying a color finish to shoes and for 100

changing the color finish from one color to another.

Having described the invention what is claimed as new is:

- 5 1. The method of refinishing leather goods which comprises applying a varnish remover to the surface, applying to the surface a coloring matter formed in part by a varnish remover and then applying a protective coat of lacquer.
- 10 2. The method of refinishing leather goods which comprises applying a varnish remover to the surface, applying to the surface a dye formed by dissolving same in a ketonic varnish remover, and then applying a film of surface protective material comprising *Rhus vernicifera* with castor and linseed oils.
- 15 3. The method of refinishing shoes which comprises applying a varnish remover to the surface and then applying to the surface a coloring matter formed in part by a varnish remover.

In testimony whereof I affix my signature.
